(57) **CLAIM**

The ornamental design for multimedia furniture, as shown and described.

DESCRIPTION

FIG. 1 is a perspective view of a design for multimedia furniture;

FIG. 2 is the perspective view without environmental elements blocking a view thereof;

FIG. 3 is a top plan view thereof;

FIG. 4 is the top plan view without environmental elements blocking a view thereof;

FIG. 5 is a bottom plan view thereof;

FIG. 6 is a front view thereof mirrored on the back side; and,

FIG. 7 is a left side view thereof mirrored on the right side.

The dashed lines in the drawings are shown for environmental purposes and form no part of the claimed design.
